(57) **CLAIM**

The ornamental design for a photovoltaic charger, as shown and described.

DESCRIPTION

1. Photovoltaic charger

Figure 1.1. is a front perspective view;

Figure 1.2 is a bottom view, in an open position;

Figure 1.3 is a top view;

Figure 1.4 is a rear view;

Figure 1.5 is a bottom view;

Figure 1.6 is a side view;

Figure 1.7 is a top view, in an open position;

Figure 1.8 is a perspective view, in an open position; and

Figure 1.9 is a front view.

In the reproductions, the broken lines are for the purpose of illustrating portions of the photovoltaic charger that form no part of the claimed design.
